HARNESS CORD FOR LOOMS AND METHOD OF MAKING SAME

Bernard E. Green, Shrewsbury, Mass.

Application March 27, 1951, Serial No. 217,765

3 Claims. (Cl. 139—88)

This invention relates to improvements in cords employed in suspending and manipulating the harnesses of looms and has particular reference to novel means and method of making and providing said cords with connection end members.

One of the principal objects of the invention is to provide harness cords of the above character which are extremely resistant to wear, resistant to deterioration in the presence of oils, which will retain their initial lengths during use and having improved connection means adjacent the opposed ends thereof whereby the said cords will more positively retain their connected relation with the harnesses and with the wires for manipulating said harnesses as is the function of such cords in looms.

Another object is to provide a cord of the above character and method of making the same having a wire cable core covered with a casing of material resistant to wear, less susceptible to deterioration under conditions of use and having connection means secured to its opposed ends in the form of initially tubular shaped members having a portion thereof overlying the ends of the cord and anchored in crimped relation therewith and another portion thereof anchored to a looped end of the cable by compression of the walls of said portion and by thereafter cupping said compressed portion to a semi-circular cross-sectional shape of a width no greater than the width of the initial diameter of its tube and having the portion of the looped end of the cable bindingly anchored therein and further having a connection opening formed through said compressed walls and in alignment with the looped end of the cable.

Other objects and advantages of the invention will become apparent from the following description taken in connection with the accompanying drawings and it will be apparent that many changes may be made in the details of construction, arrangement of parts, and steps of the method shown and described without departing from the spirit of the invention as expressed in the accompanying claims. I, therefore, do not wish to be limited to the exact details of construction, arrangement of parts and steps of the method shown and described as the preferred form only is given by way of illustration.

Referring to the drawings:

Fig. 1 is a side elevational view of the device embodying the invention and diagrammatically illustrating its use;

Fig. 2 is a side elevational view partially in section of a tubular member from which one of the attachment or connection ends of the device is formed;

Fig. 3 is a fragmentary side elevational view of one end of the cord preparatory to assembling the tubular member of Fig. 2 therewith in forming one of the connection ends;

Fig. 4 is an enlarged sectional view of one end of the device illustrating the tubular member of Fig. 2 in related position with the end of the cord and the initial position of the end of the core preparatory to performing a subsequent operation thereon;

Fig. 5 is a view generally similar to Fig. 4 illustrating a still further step of the method and showing the completed attachment or connection end member;

Fig. 6 is an enlarged sectional view taken as on line 7—7 of Fig. 5 and looking in the direction indicated by the arrows; and

Fig. 7 is a sectional view taken as on line 8—8 of Fig. 5 and looking in the direction indicated by the arrows.

2

Referring more particularly to the drawings wherein like characters of reference designate like parts throughout the several views, the device embodying the invention comprises cords of the character described adapted for use in supporting the harnesses of looms of conventional type. Prior to the present invention, these cords were formed of woven fabric having metallic members secured to the ends thereof to form connection means by which one end of the cords may be attached to the harnesses and the opposed end may be attached to the conventional wires for manipulating the harnesses. These cords are extended over sheaves and are adapted to raise and lower the harnesses by the pull and release of the manipulating wires, with the said cords riding in the grooves of the sheaves. This movement of the harnesses takes place continuously during the operation of the loom in weaving cloth or the like and, therefore, the cords must retain their initial length and must be as resistant to wear as possible. It is further pointed out that the cords soon become saturated with oil during the conventional use thereof as well as covered with dirt, grit, etc., which is present under such working conditions. Prior art cords of this nature, due to the above conditions, were relatively short lived because they were readily susceptible to wear and to deterioration in the presence of oil, dirt, etc. A further major difficulty was that of having the connection means loosen and become detached during use and thereby requiring periodic replacement.

One of the major objects, therefore, of the present invention is to provide cords of the above character which will retain their initial length during use, which are much more resistant to wear, less susceptible to deterioration, and having connection end portions which will overcome the prior art difficulty of becoming loose and detached during use or throughout the life of the cord.

Referring to the drawings, the cord 9 embodying the invention is diagrammatically illustrated in position of use, that is, in assembled relation with a sheave 10 and having its improved connection end portions 11 in connected relation with the conventional hook portions 12 of a harness 13 and the hooked end 14 of the conventional wires 15 by which the harnesses are manipulated. The cord 9, as shown throughout Figs. 3 through 7, embodies an inner core 16 of wire cable which is readily flexible and distortable and resistant to breakage and to stretching. The said core 16 is provided with an outer covering 17 of synthetic rubber-like material such, for example, as neoprene (consisting essentially of polymeric chloroprene), co-polymer of butadiene and acrylonitrile or other similar material which is resistant to attack by oil and which is extremely resistant to wear. The said covering 17 is of a controlled diameter to properly fit within the circumferential groove of the conventional sheaves 10.

In forming the cord, the opposed ends are stripped to cause a portion of the inner core 16 to extend outwardly thereof a considerable length as shown in Fig. 3. A tubular member 18, as shown in Fig. 2, having its inner bore 19 of a diameter slightly less than the outer diameter of the covering 17 and having an opening 22 extending therethrough is placed over the end of the cord, as illustrated in Fig. 4 by first forming the extended portion of the core 16 to a loop 20. The assembled tubular member 18 and looped end of the cord is then placed in one section of a die having a member adapted to extend into the opening 22 and into the loop 20 to retain them in alignment. The portion of the tubular member having the loop 20 therein is then compressed and flattened by striking it with another die section to move the opposing side walls thereof into adjacent relation with each other and in pinching relation with the loop 20 as shown best in Fig. 6. Simultaneous to this compressing of the walls, the portion of the tubular member overlying the end of the covering 17 is crimped as illustrated at 21 to aid in anchoring the tube to the cord. It is particularly pointed out that as the tube is initially flattened, as illustrated best in Figs. 5 through 7, the opposed sides 23 and 24 of the cupped portion are spaced with respect to each other a distance substantially equal to the initial diameter of the tube. This is to permit the harnesses which are normally in adjacent nested relation with each other to be free to move upwardly or downwardly with

respect to each other with no interference by the ends of the cord. It is particularly pointed out that one of the walls 25 of the tube when cupped as stated above, particularly the outer side wall, curves inwardly toward the longitudinal axis 26 of the cord along a sweeping arc as illustrated best in Fig. 7, which arc will intersect the longitudinal axis 26 at a point slightly spaced from but adjacent the outer end 27 of the flattened portion. The inner wall 28 is cupped to a cross-sectional arc of a radius less than the cupping of the outer wall 25 whereby the respective edges 29 and 30 of the flattened portion will be moved inwardly, as illustrated in Fig. 6, an amount sufficient to position them a distance apart substantially equal to the initial diameter of the tube. It is further pointed out that although the flattened end is curved as illustrated in Figs. 5 through 7, the said spaced walls 25 and 28 still retain a binding gripping relation with the looped portion 20 of the cable.

It is further pointed out that although the connection opening 22 is described as being formed in the tube at the initial stage of the process, as illustrated in Fig. 2, the said opening 22 may be formed through said inner and outer walls 25 and 28 centrally of the loop 20 after the end has been cupped.

By reference to Fig. 7, it is to be noted that the wall 28, while cupped inwardly about a radius less than the radius of the outer wall 25, it is also cupped inwardly in a sidewise direction toward the wall 25 about a radius 31 which is less than the sweeping radius of curvature of the side wall 25 in said direction. The upper end portions 32 and 33 of said spaced walls 25 and 28 are in substantially parallel relation with each other throughout the area occupied by the opening 22.

It is particularly pointed out that the inner and outer walls 28 and 25 will be in binding pinching relation with the looped portion 20 of the core throughout the length of said substantially parallel portions 32 and 33 and will provide a wide area of gripping and holding relation with the said looped portion 20.

Although the crimpings 21 are shown as being formed only in one diametrically opposed relation, similar crimpings may be formed in a substantially perpendicularly diagonally opposed relation, if desired, in addition to said first named crimping.

The ends 11 are preferably placed in assembled relation with the hooks 12 and 14 with the said ends curving inwardly with respect to the opened portions of the hooks, as shown best in Fig. 1, whereby said ends will remain more permanent in attached relation with said hooks and will not become disconnected therefrom.

From the foregoing description, it will be seen that simple, efficient and economical means have been provided for accomplishing all of the objects and advantages of the invention.

Having described my invention, I claim:

1. A harness cord of the character described comprising a main longitudinal cable portion embodying an inner metallic cable core having a looped end, an outer covering of a material resistant to oil and to wear on said core adjacent said looped end and connection means on said looped end embodying a unitary metallic tubular member with continuous unbroken walls overlying the covering adjacent said looped end and having its side walls crimped inwardly to anchor said tubular member to said covering, said tubular member having an integral portion with a first side wall compressed inwardly toward and into compressing engagement with the looped end to function cooperatively with a second side wall to intimately bind the looped end of the metallic cable core therebetween, said inwardly compressed first side wall and said second side wall being cupped sidewise in the direction of the longitudinal axis of the cord from one side of said longitudinal axis along a sweeping arc wherein the curve of the second side wall will intersect said longitudinal axis substantially adjacent the outer end of said compressed walls and said walls further being cupped to a cross-sectional arc of a radius less than said longitudinal cupping and by an amount sufficient to position the respective side edges thereof on the opposed sides of the looped portion of the core a distance apart substantially equal to the diameter of the tubular portion overlying the outer covering adjacent said looped end of the core and said cupped walls having an opening extending therethrough substantially centrally of the looped end of the core.

2. A harness cord of the character described comprising a main longitudinal cable portion embodying an inner metallic cable core having a looped end, an outer covering of a material resistant to oil and to wear on said core adjacent said looped end and connection means on said looped end embodying a unitary metallic tubular portion with continuous unbroken walls overlying the covering adjacent said looped end and having inwardly crimped wall portions to anchor said tubular member to said covering, said tubular portion having an integral portion with a first wall compressed inwardly toward a second wall by an amount to position said walls in intimate binding relation with the looped end of the metallic cable core, said compressed first wall being cupped inwardly in the direction of the longitudinal axis of the cord and said second wall being cupped sidewise substantially parallel with the first wall and to curve along a sweeping arc from one side of said longitudinal axis to a point which intersects said longitudinal axis substantially adjacent the outer end of said compressed walls and outwardly of the looped end of the core, and said walls being oppositely cupped to a cross-sectional arc of a radius less than said longitudinal cupping and by an amount sufficient to position the respective side edges of said walls on the opposed sides of the looped end of the core and said compressed walls having an opening extending therethrough substantially centrally of said looped end of the core.

3. A harness cord of the character described comprising a main longitudinal cable portion embodying an inner metallic cable core having a looped end, an outer covering of a material resistant to oil and to wear on said core adjacent said looped end and connection means on said looped end embodying a unitary metallic tubular member with continuous unbroken walls overlying the covering adjacent said looped end and having its side walls crimped inwardly to anchor said tubular member to said covering, said tubular member having an integral portion with a first wall compressed inwardly toward a second wall to position the said walls in intimate binding relation with the looped end of the metallic cable core, said first wall being cupped inwardly along a relatively short radius of curvature adjacent the outer end of the cable portion and to blend into a portion of a long radius of curvature in the direction of the longitudinal axis of the cord and the other adjacent or second side wall being curved along a sweeping arc substantially parallel with the long radius curved portion of the first wall from one side of the longitudinal axis and which intersects said longitudinal axis substantially adjacent the outer end of said compressed portion and outwardly of the looped end of the core and said walls being further cupped to a cross-sectional arc of a radius less than said longitudinal curvature and by an amount sufficient to position the respective side edges of said walls on the opposite side of the looped end of the core a distance apart substantially equal to the diameter of the tubular portion overlying the outer covering adjacent said looped end of the core and said cupped walls having an opening extending therethrough substantially centrally of the looped end of the core.
